UNITED STATES PATENT OFFICE

ALEXANDER BOYNTON, OF SAN ANTONIO, TEXAS

PACKER

Application filed October 19, 1925. Serial No. 68,496.

This invention relates to a packer for use with oil wells and has a variety of applications although being especially advantageous when used with the well cementing apparatus forming the subject-matter of my co-pending application, Serial Number 59,887.

The object of the invention is to provide a packer which when provided on a well casing will operate to prevent shale or other cavy materials occurring above producing formations in wells from migrating along the outside of the liners of the well. Loose shale and other cavy material is arrested in its downward movement by these packers which are so spaced as to come in contact with the harder formations of the well wall.

Another object of the invention resides in the provision of a packer which may be used to advantage in cementing one string wells; that is, wells where the casing and liner are of the same size. When so used the packers prevent the downward migration of the cement and, of course, to accomplish this function it is necessary to use in conjunction with the packers a plate inserted in the casing opposite the packers for the purpose of preventing the cement from going down inside the casing.

Another object of the invention is to provide a packer or sealing member of such character that when two or more of successively increasing size are mounted on a well casing they will shear off the formation making up the wall of the well so as to cause an impaction of the formation and thereby provide natural packing along with the artificial packing provided by the packing member.

Another object of the invention resides in the provision of a device of this character which has these advantages, is of simple and durable construction, reliable and effective in operation, susceptible of application to the ordinary well casing or tubing, and easy and comparatively inexpensive to manufacture.

Other objects and advantages reside in certain novel features of the construction, arrangement and combination of parts which will be hereinafter more fully described and

particularly pointed out in the appended claims, reference being had to the accompanying drawings forming a part of this specification, and in which:

Figure 1 is a view in section on the line 2—2 of Figure 2 showing the packer or sealing member constructed in accordance with the present invention.

Figure 2 is a view in horizontal section on the line 2—2 of Figure 1.

Figure 3 is a bottom plan view, and

Figure 4 is a fragmentary view in top plan.

Referring to the drawings, the numeral 1 designates the cylindrical body portion or relatively large ring member of the packer, the body portion 1 being designed to be snugly fitted on the casing or tubing and being held thereto by set screws 2. The belting washers, or washers of other flexible and pliable material, are designated at 3 and 4 and are placed against the upper side of the cylindrical body portion 1. Preferably the washers 3 and 4 have external diameters of different sizes so as to present the stepped formation shown in Figure 1. To the upper side of the washer 4 a retaining ring member 5 of soft brass is applied. The edge of the ring 5 adjacent the washer 4 is rounded off as shown at 5a. The washers 3 and 4 are compressed and held between the ring members 1 and 5 by means of nails or bars 6 having shanks 7 passing up through aligned holes in the ring member 5, the washers 4 and 3 and the ring member 1. Each nail or bar 6 has a head 8 engaged with the ring member 5 and has its terminal or outer end portion outwardly curved, as at 9, and fitted against a shoulder 10 provided by a wall of an opening 11 which communicates with the respective slot 12 in the ring member 1. The slots are formed longitudinally of the body 1 and upon the inner periphery. The nails 6 are inserted in the slots 12 and openings 11, in the latter of which they are bent around or clinched upon the shoulders 10 prior to being cut flush. The pressure would cut the upper washer 4 in two, and to prevent this the bottom edge

of the ring is rounded at 5^a, as already stated.

It is to be observed that the body 1 comprises both the element that receives a tube 5 around which a packing is to be constructed, and a mounting for the washers and the clamping means thereof. The nails 6 transfix the body in the direction of the axis, and when the washers, ring and nails are assembled upon the body 1 the resulting packer constitutes a unit construction.

An important feature resides in the formation of the washers. These are progressively larger, and as shown in Figure 1 the washers become larger in the upward direction. The advantage of this construction is this: Material sloughing off of the sides of the bore will settle upon the upper washer 4. The weight of the material will tend 20 to bend the washers, but the freedom of bending is limited by the next smaller washer which acts as a brace.

With this arrangement the packer or sealing member may be securely and rigidly 25 fixed onto the well casing or tubing and the washers are so supported and mounted as to be adapted to shear off the formation of the well hole and obtain the desired packing action and yet are permitted to partake of 30 a limited and desired degree of flexure.

What I claim is:

1. A packer for use on the outside of a well liner comprising a body fitted on the outside of the well liner, means carried by 35 the body for fastening it to said liner, a plurality of superimposed flexible and pliable washers of successively increasing diameter being positioned on top of the body and projecting outwardly therefrom, 40 a relatively small ring member engaged with the top of the uppermost washer, and nails passing through the upper ring member and the washer, the body having slots through which the nails extend and having 45 openings in its lower portion communicating with the slots of the body, said nails having their lower portions outwardly offset and engaged with said openings, whereby the nails are secured in position.

2. A packer comprising a cylindrical body with slots having openings at one edge furnished with shoulders, a plurality of washers applied to the other edge of the body, a ring on the uppermost washer, and headed 55 means transfixing the ring and washers extending along the slots and being bent around the shoulders to maintain a clamped connection of the washers.

3. A packer comprising a plurality of 60 flat, pliable washers progressively larger in one direction superimposed upon each other, a cylindrical body upon one edge of which the washers are applied so that the bores of the washers and body substantially coincide and beyond the sides of which the pe-

ripheries of the washers extend in progressively stepped relationship, a ring to bear on the uppermost washer, and a plurality of means transfixing the ring and washers, and the wall of the body in the direction of the axis of the packer to clamp the parts together.

4. A packer comprising a tubular body, and a plurality of ring-washers applied to one end of the body and having openings 75 constituting a continuation of the bore of the body to leave an unobstructed central passage, said washers being progressively larger in one direction to assume a progressively outstanding stepped relationship.
